UNITED STATES PATENT OFFICE.

WILLIAM J. PETER, OF NEW YORK, N. Y.

AUTOMATIC WATER-DISCHARGE VALVE FOR HYDRAULIC OIL-DISPENSING SYSTEMS.

Application filed July 15, 1925. Serial No. 43,702.

To all whom it may concern:

Be it known that I, WILLIAM J. PETER, a citizen of the United States, residing at New York city, in the county of Bronx, State of New York, have invented certain new and useful Improvements in Automatic Water-Discharge Valves for Hydraulic Oil-Dispensing Systems; and I do hereby declare the following to be a full, clear, and 10 exact description of the invention, such as will enable others skilled in the art to which it appertains to make and use the same.

This invention relates to hydraulic systems for storing, handling and delivering oil, and more particularly to means for filling such systems with oil and automatically controlling the quantity of oil introduced.

In hydraulic systems for storing, handling and delivering oil, the storage tank is 20 always filled with liquid, oil and water, the oil overlying the water. In dispensing, the oil is forced out through a pipe in the top of the tank by forcing water in through the bottom. In filling the tank with oil the 25 pressure is reversed, the oil being forced in through the top of the tank and the water out through the bottom and to waste. In order to prevent oil from following the water into the drain some means must be 30 provided, either for indicating that the tank has been filled, or for automatically arresting the flow.

In my co-pending application, Serial No. 18,783, filed March 27, 1925, I have disclosed and claimed mechanism for automatically arresting the influx of the oil when the tank has been filled. This mechanism comprises a valve situated in the oil intake pipe normally open and connected to a float situated 40 near the bottom of the tank and designed to float in water and sink in oil. When the oil level, during the filling operation, reaches the float it sinks and automatically closes the intake valve, thus effectively preventing further influx of oil and making it 45 impossible for any oil to follow the water through the water discharge pipe and to the sewer.

In accordance with the present invention 50 I have devised a mechanism for accomplishing this same result by providing the water discharge pipe with a valve and providing float operated means for automatically closing this valve when a predetermined amount 55 of oil has been introduced into the tank, the water discharge pipe being so constructed

that the cut-off valve is situated near the top of the tank and the controlling valve near the bottom. There is thus a substantial distance between the oil level and the 60 valve at the time of the cut-off and the water discharge pipe between the float and the valve being filled with water at this time, there is no possibility that oil may escape past the valve as it is closing and pass to 65 waste.

During the operation of filling the tank with oil, the source of hydraulic pressure employed during the dispensing operation of the tank is shut off and is not again put 70 in communication with the tank until the oil is to be dispensed. Hence, at the time when the tank has been filled, the valve in the water discharge pipe automatically closed and the cap placed upon the oil intake pipe, the tank is completely sealed. In order to prevent rupture due to expansion 75 of the contained liquid during this period, I provide the tank with some sort of pressure relief means. As soon as the tank 80 is used to dispense oil and the oil level rises beyond the float, the valve in the water pipe is automatically opened and the tank is thereafter never under pressure greater than 85 that of the hydraulic operating means, and when not in operation is actually open to the sewer.

In the accompanying drawings I have illustrated, more or less diagrammatically, 90 certain preferred embodiments of my invention. In these drawings Figure 1 is a longitudinal section through a tank equipped with the water discharge control valve of the present invention, the section through the valve being taken along line 1-1 of 95 Figure 3; Figure 2 is a similar view of a modified form of construction in which the water discharge pipe is external of the tank; Figure 3 is a plan view of a manhole cover on which the valve housing of the water discharge control valve is mounted, as well 100 as the valve housing of the oil discharge control valve, the construction and operation of which is described and claimed in 105 my co-pending application, Serial No. 18,782, filed March 27, 1925; Figure 4 is a section taken along line 4-4 of Figure 3 showing the construction of the oil discharge control valve and its operating mechanism which forms no part of the present invention; Figure 5 is a fragmentary longitudinal section through an oil tank equipped 110

- 2
- with a modified form of valve and showing the connection between the float and the valve extending within the water discharge pipe.
- 6 Referring first to Figure 1, the storage tank is indicated by reference numeral 1. This is the ordinary cylindrical storage tank used in most systems and is commonly placed within an excavation with its longitudinal axis horizontal. The oil is introduced through an intake pipe 2 equipped with a filling plug 3 and discharged through a riser 4 having a valve 5, both pipe 2 and riser 4 entering the top of the tank as indicated, while the water is introduced and discharged through a pipe 6 which enters the tank at the top and extends downwardly to a point near the bottom. In the system illustrated the water pressure is obtained by
- 10 maintaining a constant head in a riser 7 which is connected with the pipe 6 through a valve 8. The upper end of the riser 7 terminates in a float box 9 into which water is fed through a feeder pipe 10 from any
- 15 convenient source, such as the city water mains, the level of the water in the float box being automatically maintained constant by means of a float valve 11. A valve 12 placed between the pipe 6 and the drain 13 controls the connection between the tank and the drain. Valves 8 and 12 are preferably operated simultaneously by means of a valve rod 14 and the connections are so designed that when valve 8 is opened, valve 12 is
- 20 closed, and vice-versa.
- The system just described is commonly known as a constant head hydraulic system and, of itself, forms no part of the present invention. I shall, however, describe briefly the manner in which this system operates. During the filling of the tank, valve 8 is closed and valve 12 opened, thus connecting the water pipe 6 with the drain 13. Oil is then forced into the pipe 2 and forces the water out through the pipe 6 to the drain. During delivery of oil the valve 8 is opened and the valve 12 closed so that the pressure of the constant head maintained in riser 7 by the float valve 11 forces oil up the riser 4 and out. When the tank is not in actual use, valve 8 is preferably closed and valve 12 opened so that the tank is not under pressure. The valve 5 thus acts merely as a locking means and does not necessarily form a part of the operating mechanism.
- 25 The present invention relates to the water discharge control valve and its attendant mechanism which I shall now describe in detail. The upper end of that part of the water discharge pipe 6 which lies within the tank leads into a valve housing 15 integral with a manhole cover 16 and thence to an outer section of the pipe 6 to the drain 13. Mounted within the valve housing 15 is a valve 17 adapted, when closed, to be seated
- upon a valve seat 18, which extends across the housing 15. The valve 17 is pivotally mounted upon a pin 19 and is swung upwardly into closed position by means of an arm 21, but normally lies in open position as shown. A float 23 is pivotally mounted at 24 near the bottom of the tank upon the lower end of a bar 25 depending from the manhole cover 16. The end of the float stem 26 beyond the pivot point is connected by means of a rod 27 with a bellcrank lever 28 also pivoted upon the bar 25. The upper end of the bellcrank lever 28 is designed to contact with the lower end of the arm 21 and when swung upward to close the valve. The float 23 is designed to float in water, but sink in oil and thus the position of the valve 17 is determined by the oil and water level in the tank.
- 30 The water discharge control valve operates as follows during the filling of the tank with oil: Assuming that the tank is filled with water and that it is necessary to refill it with oil, the valve 8 is closed and the valve 12 opened, throwing the tank into communication with the sewer. As the tank is now full of water the float 23 is in its uppermost position and the valve 17 therefore open, as shown in Figure 1. A hose from a tank wagon or other source of supply is connected to the filling plug 3 of the intake pipe 2 and oil permitted to flow by gravity into the tank, displacing because of its greater head, the water, which is forced out through pipe 6 past the open valves 17 and 12 to waste. As long as the oil and water level, remains above the float 23 and more oil is forthcoming, this action will continue. When, however, the oil reaches the float 23, the latter sinks thereby swinging the valve 17 into closed position upon the seat 18 and arresting further discharge of water. The moment valve 17 is closed, further influx of oil is automatically stopped. It will be noted that the force of the water current flowing past the valve is sufficient of itself to seat the valve the moment it is swung into the path of flow. Thus, the closing action is quick and positive, and, due to the position of the float occurs before the oil level has reached the open end of the pipe 6, hence there can be no danger of oil escaping to the sewer.
- 35 It will be observed that after the valve 17 is closed at the termination of the filling operation and the plug 3 closed, the system is completely closed and will remain so until the oil is to be delivered. Thus during this period any expansion of the liquid in the tank, due to a rise in temperature, might cause trouble. I therefore provide pressure relief means in the form of a pipe 30 communicating with the tank through the valve housing 15. This pipe is provided with a valve 31 which can be opened at the termi-

nation of the filling operation and thus permit the liquid in the tank to expand without danger. The system is closed, however, only until delivering begins when the valves 8 and 5 are opened and the valve 31 closed. Water from the float box 9 thus flows through pipe 6 past the closed valve 17, swinging the latter downward in its passage, and into the tank, thereby forcing oil out through riser 4. The pressure of the inflowing water is sufficient to swing the valve 17 from its seat. As soon, however, as sufficient oil has been dispensed to raise the oil and water level to the float 23, the latter rises swinging the outer end of the bell-crank lever 28 downward thus permitting the valve 17 to drop by its own weight into open position where it remains during the rest of the normal operation of the tank. As the valve 12 is opened when the valve 8 is closed and no oil is being delivered, the system is open to the sewer when idle and there is no possibility of danger from expansion.

In Figure 2 I have illustrated a construction which is identical in every way with that shown in Figure 1 except that here the pipe 6 is external of the tank. The operation is the same and need not be repeated. In order to simplify the installation, I mount the oil discharge control valve and the water discharge control valve on a single manhole cover as illustrated in Figure 3. The oil discharge control valve 32 is contained within a housing 33 similar to the housing 15 and is structurally very similar to valve 17, just described. The operation of this valve which is illustrated in detail in Figure 4 has been described fully in my co-pending application Serial No. 18,782 and as it forms no part of the present invention will not be repeated here.

In Figure 5 I have illustrated a still further modified construction. Here the float 23 is pivoted upon and directly supported by the pipe and the connecting rod 27 passes through the pipe 6 to the valve 34 which is mounted for vertical movement directly above the lower section of the pipe 6 and enclosed within a housing 35. The operation is exactly the same as that described in Figure 1, except that here there are fewer parts intermediate the float 23 and the valve.

Instead of providing a pressure relief pipe opening into the air and provided with a manually operated valve I have illustrated in Figure 5 a pipe 36 extending from the

valve housing 35 just below the valve and entering the float box 9 above the water level. Any water forced out of this pipe due to expansion of the tank will simply be returned to the system through the float box 9. As no oil can rise within the pipe 6 there is no danger that any oil will be discharged through the pipe 36. This same result can be obtained by running the pipe 36 into the pipe 7 above the water control valve and placing a check valve in the pipe 36 preventing downward movement of water through the pipe 36 and into the tank.

I claim:

1. In a hydraulic oil storage and delivery system, the combination of a tank, an oil intake, a water discharge pipe opening at or near the bottom of the tank and extending to or near the top, a valve in the water pipe situated near the top of the tank, a float near the bottom of the tank designed to float in water and sink in oil, and means connecting the float and the valve so that when the oil level reaches the float, the valve is closed.

2. In a hydraulic oil storage and delivery system, the combination of a tank, an oil intake, a water discharge pipe, a valve in the water pipe, and a float within the tank situated a substantial distance below the valve for closing the valve when the oil level reaches the float thereby preventing further discharge of water and influx of oil.

3. In a hydraulic oil storage and delivery system, the combination of a tank, an oil intake, a water discharge pipe extending from the top of the tank to a point near the bottom, a valve in the pipe near the top of the tank, a float designed to float in water and sink in oil, mounted near the lower end of the pipe and means connecting the float and the valve so that when the oil level reaches the float the valve is closed.

4. In a hydraulic oil storage and delivery system, the combination of a tank, an oil intake, a water discharge pipe extending from the top of the tank to a point near the bottom, a valve in the pipe near the top of the tank, a float designed to float in water and sink in oil pivotally mounted upon the lower end of the pipe and a rod connecting the float and the valve and extending through the pipe in such a manner that when the oil level reaches the float the valve is closed.

In testimony whereof I affix my signature.

WILLIAM J. PETER.
